The ornamental design for a desktop scanner, as shown and described.

DESCRIPTION

FIG. 1 is a perspective view of a desktop scanner in accordance with the present invention;

FIG. 2 is a front view thereof;

FIG. 3 is a right side view thereof;

FIG. 4 is a rear view thereof;

FIG. 5 is a left side view thereof;

FIG. 6 is a top plan view thereof; and,

FIG. 7 is a bottom plan view thereof.

Broken lines and portions contained within broken lines are not claimed.
